UNITED STATES PATENT OFFICE.

JOHN CAMERON GRANT, OF BARNES, LONDON, ENGLAND.

PROCESS OF ELEVATING LIQUIDS.

Application filed December 8, 1920. Serial No. 429,207.

To all whom it may concern:

Be it known that I, JOHN C. GRANT, a subject of the King of Great Britain and Ireland, residing at Holly Lodge, The Terrace, Barnes, London, England, have invented certain new and useful Improvements in the Processes of Elevating Liquids, of which the following is a specification.

The object of the present invention is to improve the art of elevating liquids semiliquids, etc., particularly water, oils, syrups or water mixed with clay or other matter.

In my prior Patent No. 1,358,632 I have described an apparatus particularly adapted to carry out my improved process but I have found that my improved process may be performed by other and varied forms of apparatus hence my improved process while illustrated with the apparatus of my prior patent is not limited to any particular apparatus.

I have found that if an open structure such as a chain or succession of open helices or the like be passed through a body of liquid and raised with sufficient velocity, large quantities of the liquid will adhere to the loose structure by capillary attraction and be raised with the structure. The particles or portions of the liquid adhering to the open ascending structure will carry other particles so that if the ascent be sufficiently rapid a practically solid column of ascending liquid will be formed on all sides of the open structure, then after the liquid has been elevated to the desired height if the open structure be run around a circle or part of a circle at a sufficiently rapid speed the centrifugal force developed together with the inertia of the column of liquid can be so utilized that practically all the liquid from all sides of the open structure will leave it and the open structure can then be returned to the body of liquid practically dry.

In the accompanying drawings which illustrate a method of practicing this invention Fig. 1 is a sectional view showing the operation of the invention. Fig. 2 is a sectional view of a part of the open structure and Fig. 3 is a view at a right angle to the view in Fig. 2.

Numeral 1 designates individual coils of a helix or the like which may be conveniently overlapped and rods 2 passed through the overlapped portions to hold the helices in

their relative positions. 4 designates links between the rods to take the strain or weight off the helices and 5 designates a wheel or the like turned by a suitable source of power, not shown.

When wheel 5 is turned sufficiently rapidly a column of liquid will be elevated and as the open structure turns around the wheel if the wheel is rotated at the proper speed the liquid will practically all leave the wheel and the structure will return practically dry.

The essence of this invention is that the wheel 5 must be of such size and be run at such speed that the centrifugal action and momentum of the column will cause practically all the liquid to leave the structure, but to accomplish this result I have found that the wheel must be run at different speeds for different liquids some liquids or semiliquids requiring a higher rate of speed than others to completely separate the liquid from the open structure. On the other hand some structures require different rates of speed to separate the same liquid from what is required for other structures.

Having described one method of practicing my invention I do not intend to be limited to the exact details but expect the doctrine of equivalents to apply to the appended claims.

1. The method of elevating a liquid or semiliquid which consists in passing through the liquid an open structure supported only at its ends thus permitting a solid column of liquid to be lifted unimpeded until freed from the structure by centrifugal action, then elevating the open structure rectilinearly sufficiently fast to form a column of liquid on all sides of the open structure changing the rectilinear motion of the structure to a circular motion but still causing the liquid to rise on both the inner and outer sides of the liquid column unobstructed and then continuing the circular motion of the structure sufficiently rapidly to develop forces great enough to separate the liquid on both sides of the open structure from the same.

2. The method of lifting a liquid or semiliquid which consists in passing through the liquid an open structure, guided and supported so that a column of liquid may be lifted unimpeded on both the inner and outer sides of the open structure, lifting the

structure rectilinearly sufficiently fast to form a column of liquid on both the inner and outer sides of the open structure, changing the rectilinear motion to a circular motion without obstructing the column of liquid on either the inner or outer side of the open structure, operating the structure

sufficiently rapidly to develop centrifugal forces great enough to separate the liquid on both sides of the open structure from the 10 structure and to project it beyond the confines of the open structure.

In testimony whereof I affix my signature.
JOHN CAMERON GRANT.
